CLAIM

The ornamental design for a hitch-mount bicycle carrier, as shown and described.

DESCRIPTION

FIG. 1 is a perspective view of the hitch-mount bicycle carrier.

FIG. 2 is a front elevational view of the hitch-mount bicycle carrier.

FIG. 3 is a rear elevational view of the hitch-mount bicycle carrier.

FIG. 4 is a right side elevational view of the hitch-mount bicycle carrier.

FIG. 5 is a left side elevational view of the hitch-mount bicycle carrier.

FIG. 6 is a top plan view of the hitch-mount bicycle carrier; and,

FIG. 7 is a bottom plan view of the hitch-mount bicycle carrier.

The broken lines immediately adjacent the shaded areas represent the bounds of the claimed design while all other broken lines are directed to environment and are for illustrative purposes only; the broken lines form no part of the claimed design.
